(57) **CLAIM**

The ornamental design for a micro flow channel chip, as shown and described.

DESCRIPTION

FIG. 1 is a front elevational view of a first embodiment of a micro flow channel chip showing our new design, with the rear elevational view being a mirror image thereof;

FIG. 2 is a top plan view of the micro flow channel chip of FIG. 1, with the bottom plan view being a mirror image thereof;

FIG. 3 is a left side elevational view of the micro flow channel chip of FIG. 1, with the right side elevational view being a mirror image of the micro flow channel chip of FIG. 1;
FIG. 4 is a front-bottom-left perspective view of the micro flow channel chip of FIG. 1;

FIG. 5 is a partially enlarged perspective view of the micro flow channel chip shown in FIG. 4;

FIG. 6 is a front elevational view of a second embodiment of a micro flow channel chip showing our new design, with the rear elevational view being a mirror image thereof;

FIG. 7 is a top plan view of the micro flow channel chip of FIG. 6, with the bottom plan view being a mirror image thereof;

FIG. 8 is a left side elevational view of the micro flow channel chip of FIG. 6, with the right side elevational view being a mirror image thereof;

FIG. 9 is a front-bottom-right perspective view of the micro flow channel chip of FIG. 6;

FIG. 10 is a partially enlarged perspective view of the micro flow channel chip shown in FIG. 9;

FIG. 11 is a front elevational view of a third embodiment of a micro flow channel chip showing our new design, with the rear elevational view being a mirror image thereof;

FIG. 12 is a top plan view of the micro flow channel chip of FIG. 11, with the bottom plan view being a mirror image thereof;

FIG. 13 is a left side elevational view of the micro flow channel chip of FIG. 11, with the right side elevational view being a mirror image thereof;

FIG. 14 is a front-bottom-left perspective view of the micro flow channel chip of FIG. 11; and,

FIG. 15 is a partially enlarged perspective view of the micro flow channel chip shown in FIG. 14.
